FLUSH VALVE

Howard F. Kelso, Houston, Tex., assignor to The Beaton & Cadwell Manufacturing Company, New Britain, Conn., a corporation of Connecticut

Application August 12, 1930, Serial No. 474,777

10 Claims. (Cl. 137—93)

This invention relates to valves, and more particularly to a flushing valve which will produce the same period of flush irrespective of the length of time the actuating handle is pressed down.

One object of the invention is to provide a flush valve of the above nature which will deliver only a single flush even though the actuating handle is held down continuously or is operated several times in quick succession.

A further object is to provide a flush valve of the above nature which will be simple in construction, inexpensive to manufacture, easy to install and manipulate, fool-proof, compact, ornamental in appearance, and very efficient and durable in use.

With these and other objects in view there has been illustrated on the accompanying drawing one form in which the invention may be conveniently embodied in practice.

In the drawing:

Fig. 1 represents a vertical side sectional view of a flush valve embodying the invention.

Fig. 2 is a side view of the flush valve, shown on a somewhat reduced scale.

Referring now to the drawing in which like reference numerals denote corresponding parts throughout the several views, the numeral 10 indicates the body member of the flush valve having a horizontal side inlet port 11 and a vertical bottom outlet port 12. The side inlet port 11 is adapted to be connected to a water supply pipe, not shown, by means of a pair of cooperating coupling members 13 and 14.

The top of the outlet port 12 terminates in a thin annular rim 15 forming a seat for a hollow main valve consisting of an upper section 16 and a lower section 17, the latter being provided with a plurality of vertical guiding vanes 18 adapted to slidably fit within the outlet port 12. The lower section 17 of the main valve has a flat base 18a provided with a central aperture 19 upon which rests a rubber gasket 20 forming a seat for the head 21 of a release valve, and depending from said head 21 is a normally vertical rod 22. The rod 22 is located in alignment with a horizontal actuating rod 23 forming part of the valve operating mechanism. The rod 23 terminates at its outer end in an enlarged piston 24 which is adapted to slide in a cylinder 25 in a laterally extending projection 25a of the body member 10. The piston 24 is adapted to be engaged by the tiltable head 25b of an operating handle 26 normally lying in a horizontal position, as shown in Fig. 1. The inner side of

said piston 24 is engaged by a coiled spring 26a located within the cylinder 25 surrounding said rod 23. The head 25b is located in an adjustable recess 26b and is held in place by an in-turned flange 26c formed on a cap member 26d screwed upon the outside of said side projection 26a. By means of this construction, it will be seen that when the handle 26 is swung in any direction, the head 25b will tilt in the recess 26b and cause the piston 24 to slide inwardly, 10 rocking the depending rod 22 upwardly and to the right, as shown in Fig. 1. This action will raise the head 21 of the release valve off of its seat and let out a small quantity of water from the interior 27 of the main valve, which space 15 will be hereinafter termed the "release chamber".

The upper section 16 of the main valve is threaded at its lower end so that it may be screwed into the upper end of the lower section 17. The upper section 16 has a horizontal flange 28 at its top, the edge 29 of which is threaded. The space within the upper part of the flush valve is divided into two chambers which will hereinafter be termed the "main chamber" 30 and the "control chamber" 31. The chambers 30 and 31 are separated by means of a flexible diaphragm 32, preferably constructed of rubber. The inner portion of the diaphragm 32 is provided with an enlarged cylindrical depending section 32a which is adapted to be held tightly between the upper and lower sections 16 and 17 of the main valve, and will rest upon the top of the rim 15 for normally closing the outlet port 12. The outer horizontal edge of said diaphragm 32 is held rigidly upon a vertical threaded upper rim 33 of the body member 10 by means of a cover member 34 having a depending annular flange 34a screwed upon said rim 33.

The top of the control chamber 31 is closed by a curved dome 35 preferably constructed of copper and having a flat outer flange 36 seated upon a metal washer 37. The dome flange 36 and the washer 37 are adapted to be tightly clamped upon the outer edge of the diaphragm 32 by the cover member 34 which preferably has a hexagonal nut section 38 upon its top for convenience in manipulation.

In order to provide means for producing a single fixed-period flush irrespective of the length of time the actuating handle 26 may be held down, or even if the valve is actuated several times in quick succession, provision is made of a check valve 39. As clearly shown in Fig. 1, said check valve 39 is adapted to be forced 55

down upon the top of the main valve by striking the dome 35 when the main valve is fully open. The release chamber 27 of the main valve will thus be closed and further escape of water from the control chamber will be prevented.

The check valve 39 has a depending section 40 located in the release chamber 27 of the main valve. The depending section 40 has a lower reduced end 41 surrounded by a coiled spring 42, the lower end of which fits around a lug 43 on the top of the release valve head 21. The spring 42 is adapted to normally hold the check valve 39 in the raised position shown in Fig. 1.

Fig. 1. 15 The check valve 39 has a horizontal upper disc section 44, the underside of which is provided with an annular inclined rib 45 adapted to seat upon a circular gasket 46, preferably constructed of rubber. A small "bleed" groove 45a is preferably formed in said rib for a purpose to be described later. The gasket 46 is held upon the upper top section 16 of the main valve by a flanged ring member 47 screwed upon the outer threaded edge 29 of the flange 28.

25 For permitting the rise of the main valve to be adjusted, provision is made of a button member 48 having a depending threaded shank adapted to be screwed into the central part of the check valve 39.

30 In order to restore the pressure in the control chamber 31 after the flush valve has been operated, provision is made of a rotary bypass plug 49, the operation of which is fully described in the previous patent to Cadwell and Ott, No. 1,657,817. The rotary plug 49 has a central horizontal passage 50 communicating with the main chamber 30 and a vertical passage 51 adapted to be selectively joined to a vertical passage 52 in the body member 10. The vertical passage 52 is provided at its upper end with an enlarged circular cavity 53, above which is a small tubular member 54 within which a ball check valve 55 is seated. The ball check valve 55 serves to prevent back siphonage in case the pressure in the inlet pipe should fall below normal, but does not interfere with the action of the bypass. The tubular member 54 has a side aperture 56 at its top edge located in alignment with a horizontal passage 57 in the washer 37, leading into the interior of the control chamber 31.

Operation

Whenever it is desired to operate the flush valve, the handle 26 will be rocked in any desired direction, causing the piston rod 23 to move inwardly and rock the release valve head 21 off of its seat. A small quantity of water will thus be allowed to escape from the release chamber 27, said water passing out through the outlet port 12. As will be clearly understood, the pressure in the control chamber 31 will thus be reduced below that existing in the main chamber 30.

The greater pressure below the diaphragm 32 will then quickly force the main valve upwardly off of its seat and will open communication between the inlet port 11 and the outlet port 12. The main valve will be guided within the outlet port 12 while rising to open position by the vanes 18 and will force the check valve 39 upwardly until the adjustable button 48 on the top thereof strikes the dome 35 covering the control chamber 31. The annular rib 45 on the bottom of the check valve disc 44 will thus be caused to tightly press down upon the gasket

46 on the top of the main valve, thereby closing the release chamber 27 therein and preventing further escape of water from the control chamber 31.

The main valve will remain raised to permit the flow of the flushing stream until the pressure in the control chamber 31 has been restored to normal by the slow leakage of water thereinto from the main chamber 30 through the bypass. Since the pressure in the two chambers will then be equalized, the main valve will be caused to close due to its weight and the resiliency of the rubber diaphragm 32. The flushing stream will be thereby shut off.

After the closing of the main valve, the check valve will remain seated upon the top of the main valve so long as the release valve 21 remains open. When the operating handle 26 is released, the release valve 21 will be restored to its seat and the slow leakage of water from the control chamber 31 to said release chamber through the bleed groove 45a on the under side of the rib 45 will permit the spring 42 to force the check valve 39 upwardly to its original normal position.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

sized to secure letters Patent is:

1. In a flush valve, a "main" chamber, a "control" chamber, a flexibly supported main valve separating said chambers, said main valve having an interior "release" chamber, means for releasing a small quantity of liquid from said "release" chamber to reduce the pressure in said "control" chamber and cause the main valve to rise and start the flushing stream, spring-supported means carried by and connected with said main valve for closing said "release" chamber when said main valve rises, and a by-pass for slowly restoring the pressure in said "control" chamber to permit said main valve to close automatically after a fixed interval of time.

2. In a flush valve, a main chamber, a control chamber, a main valve separating said chambers, said main valve being hollow and normally having open communication with said control chamber, a release valve in the bottom of said main valve for permitting the escape of water from said control chamber when the flush valve is actuated for causing the main valve to rise, a check valve located in said control chamber and carried by said main valve, and adapted to strike the top of said control chamber to close said communication when the main valve rises, thus preventing further escape of water from the control chamber, and a bypass connecting said chambers to slowly restore the pressure in said control chamber and permit said main valve to close. 63

3. In a flush valve, a main chamber, a control chamber, a main valve separating said chambers, said main valve being hollow and normally having open communication with said control chamber, a release valve in the bottom of said main valve for permitting the escape 75

- of water from said control chamber when the flush valve is actuated for causing the main valve to rise, a check valve located at the top of said main valve, a coiled spring in said main valve and seated on said release valve, said check valve resting on said spring and normally held above said main valve and adapted to close said communication when the main valve rises, thus preventing further escape of water from the control chamber, and a by-pass connecting said chambers to slowly restore the pressure in said control chamber and permit said main valve to close. 5
4. In a flush valve, a main chamber, a control chamber, a main valve separating said chambers, said main valve being hollow and normally having open communication with said control chamber, a release valve in the bottom of said main valve for permitting the escape of water from said control chamber when the flush valve is actuated for causing the main valve to rise, a check valve located at the top of said main valve, a coiled spring in said main valve, said check valve resting on said spring and normally held above said main valve and adapted to close said communication when the main valve rises, thus preventing further escape of water from the control chamber, and a by-pass connecting said chambers to slowly restore the pressure in said control chamber and permit said main valve to close. 10
5. In a flush valve having a main chamber, a control chamber, a by-pass, a flexible main valve separating said chambers and being adapted to control the flow of a flushing stream from the inlet to the outlet of said flush valve, said main valve having a central passage provided at its bottom with a release valve and carrying upon its top a check valve, actuating means to open said release valve to permit said main valve to rise, said check valve being forced against the top of said control chamber by the rising of the main valve to permit water to flow through said by-pass and slowly restore the pressure in said control chamber to cause said main valve to close, said check valve having a depending guide and a spring surrounding said guide for pressing said release valve upon its seat. 15
6. In a flush valve having a main chamber, a control chamber, and a by-pass, a flexible main valve separating said chambers and being adapted to control the flow of a flushing stream from the inlet to the outlet of said flush valve, said main valve having a central passage provided at its bottom with a release valve and at its top with a check valve, and actuating means to open said release valve to permit said main valve to rise, said check valve being forced against the top of said control chamber by the rising of the main valve to permit water to flow through said by-pass and slowly restore the pressure in said control chamber to cause said main valve to close, said check valve having an adjustable upper button to permit the time of closing of the check valve to be varied. 20
7. In a flush valve having a main chamber, a control chamber, a by-pass, a flexible main valve separating said chambers and being adapted to control the flow of a flushing stream from the inlet to the outlet of said flush valve, said main valve having a central passage provided at its bottom with a release valve and at its top with a check valve, and actuating means to open said release valve to permit said main valve to rise, said check valve being forced against the top of said control chamber by the rising of the main valve to permit water to flow through said by-pass and slowly restore the pressure in said control chamber to cause said main valve to close, said check valve having a depending guide and a spring surrounding said guide for pressing said release valve upon its seat. 25
8. In a flush valve having a main chamber, a control chamber, a by-pass, a flexible main valve separating said chambers and being adapted to control the flow of a flushing stream from the inlet to the outlet of said flush valve, said main valve having a central passage provided at its bottom with a release valve and carrying upon its top a check valve, and actuating means in alignment with said rod to open said release valve to permit said main valve to rise, said check valve being forced against the top of said control chamber by the rising of the main valve to permit water to flow through said by-pass and slowly restore the pressure in said control chamber to cause said main valve to close, said check valve having a depending guide and a spring surrounding said guide for pressing said release valve upon its seat. 30
9. In a flush valve, a main chamber, a control chamber, a movable main valve separating said chambers, said main valve having an interior release chamber, a valve in the bottom of said chamber adapted when open to release a small quantity of liquid from said release chamber to reduce the pressure in said control chamber and cause the main valve to rise and start the flushing stream, a check valve carried by said main valve and adapted to be forced against the top of said control chamber by the rising of said main valve for closing said release chamber, and a by-pass for slowly restoring the pressure in said control chamber to permit said main valve to close automatically after a fixed interval of time, said by-pass having an enlarged cylindrical chamber, a tubular valve plug seated in said chamber and having a ball seated on the top thereof, the bottom of said plug leading to said main chamber and the top leading to said control chamber. 35
10. In a flush valve, a casing, a dome-shaped detachable cover therefor, a movable main valve dividing said casing into a main chamber and a control chamber, means to release a small quantity of liquid from said control chamber to cause the unbalanced pressure in said main chamber to unseat said main valve and start the flushing stream, a by-pass for connecting said main chamber with said control chamber, and for slowly restoring the pressure in said control chamber to normal automatically at a predetermined time after said releasing means has ceased to operate, whereby said main valve will close, said by-pass including an enlarged cylindrical chamber, a tubular removable valve plug seated in the bottom of said cylindrical chamber and having a restricted lower seat, and a ball valve resting upon said seat for preventing back siphonage in case the pressure in the inlet pipe should fall below normal, said plug having a side slot in its upper portion leading laterally into said control chamber, said plug being held in place by said cover. 40
